United States Patent Office

Des. 193,783
Patented Oct. 9, 1962

193,783

CARD READER ENCLOSURE

Charles F. Grossman, Phoenix, Ariz., assignor to General
Electric Company, a corporation of New York

Filed Aug. 23, 1961, Ser. No. 66,467

Term of patent 14 years

(Cl. D26—5)

FIG. 2

FIG. 1 is a perspective front three-quarter view of a card reader enclosure showing my new design.

FIG. 2 is a perspective rear three-quarter view of same.

The dominant features of my design reside in the portions shown in solid lines.

I claim:

The ornamental design for a card reader enclosure, as shown and described.
